UNITED STATES PATENT OFFICE.

JOHN F. PFEIFFER, OF SEATTLE, WASHINGTON.

CONTINUOUS FREEZER.

1,396,972.

Specification of Letters Patent. Patented Nov. 15, 1921.

Application filed June 2, 1920. Serial No. 386,116.

To all whom it may concern:

Be it known that I, JOHN F. PFEIFFER, a citizen of the United States of America, and resident of the city of Seattle, in the county 5 of King and State of Washington, have invented certain new and useful Improvements in Continuous Freezers, of which the following is a specification.

My invention relates to a freezer designed 10 for freezing liquids so as to form thin flakes and to do this in a manner which is continuous, whereby the unfrozen liquid may be fed to a moving apparatus upon which it may be frozen and then removed in thin flakes.

15 The object of my invention is further to produce a device of this character of an improved and simple construction and one which will insure the formation of flakes of comparatively small size, rather than large 20 scales.

The features of my invention which I deem to be new will be first described and then particularly defined by the claims.

In the accompanying drawings I have 25 shown my invention embodied in the forms of construction which I prefer to use.

Figure 1 shows an elevation of my device, the freezing chamber and its contained parts being shown in section.

30 Fig. 2 is a horizontal section through the freezing chamber taken above the belt which forms the freezing surface.

Fig. 3 is a side elevation of my device with one end of the freezing chamber shown 35 in section.

In my invention I employ as the freezing surface an endless belt 1, which is mounted upon two pulleys 10 and 11 located at opposite ends of the freezing chamber. These 40 pulleys may be turned in any suitable manner. The means illustrated consists in extending the shaft of one of the pulleys through the side wall of the casing 3 and providing it with a pulley, as 12, by which it 45 may be driven.

The freezing chamber consists of a box or casing 2, which is, of course, made of such a construction as to maintain a low temperature within the casing without excessive radiation. Within this freezing 50 chamber are pipe sections 3, in which is circulated a refrigerating liquid, these pipes being disposed adjacent to the belt 1 and also so as to have a refrigerating effect upon the 55 hopper or bin 4, which receives the material

after freezing. The arrangement of these pipes may be varied as desired or found necessary. I prefer that certain of these pipes be placed so as to extend between the upper and lower runs of the belt 1 and they may 60 also be placed under and above the outside of these runs. The placing of these pipes is to a considerable degree optional.

A tank 5, outside of the casing 2, holds the material to be frozen. This tank is 65 placed at such a position that the liquid will flow by gravity to the belt which serves as the freezing surface. The position of this tank may, however, be lowered if air pressure is applied thereto for elevating the 70 liquid, or this may be secured by the use of a pump. These are, however, expedients which would be obvious to any mechanic.

From the tank 5 extends a pipe or spout 50, into the casing 2, with its discharge end 75 over one of the pulleys carrying the belt 1. I do not, however, discharge the liquid upon the freezing belt as a broad riband, but instead, divide the discharge opening at the end of the spout 50 into a series of openings, 80 as are shown at 51 in Fig. 1. This secures the deposit upon the freezing surface of a series of narrow strips, or ribands, which are each distinct and separated from the others. As the belt 1 progresses about its 85 pulleys, these strips of liquid are congealed and when they reach the end of the lower run are scraped off, as by a scraper 6 which engages with the under surface of the belt. These, when scraped off, drop into the hopper 4 and may be retained therein or conducted to another container, as desired.

I prefer to construct the tank 5 with a double or false bottom, as 52, which bottom is provided with a series of perforations 53, 95 through which air may be discharged into the contents of the tank. This air may be provided through a pipe 70 leading from a tank 7, or any other source of air under pressure. This air passing up through the liquid 100 will serve to keep it thoroughly mixed until it has been discharged and frozen.

At one side of the casing 2 which forms the freezing chamber I provide a door, as 20, upon which is mounted the shafts which carry the wheels 10 and 11, over which the belt passes. In consequence this entire apparatus may be readily removed from the casing by opening the door, thus facilitating its thorough and easy cleaning. The 110

refrigerating pipe 3 which extends between the runs of the belt will not interfere with its swinging in and out.

By depositing the liquid upon the freezing surface in a series of narrow strips, these when removed by the scraper, are broken up into quite small flakes, thus producing a product which is more acceptable than if it should come off in large scales, as would often occur when the liquid is applied as a broad film. The product is therefore more attractive than it would be if the material was frozen as a broad sheet. I have found that material made in this way presents a very attractive appearance and also holds up without melting better than the same material frozen in the usual manner.

What I claim as my invention is:

1. A continuous freezing apparatus for liquids comprising a casing, a section at one side of the casing being hinged to swing outward, an endless belt supported from said

swinging section, refrigerating pipes within the casing and adapted to extend between and outside of the runs of the belt, a tank, a delivery spout extending from the tank to discharge upon the belt, and a scraper at the under side of the belt.

2. A continuous freezing apparatus for liquids comprising a casing, a section at one side of the casing being hinged to swing outward, an endless belt supported from said swinging section, refrigerating pipes within the casing and adapted to extend between and outside of the runs of the belt, a tank, a delivery spout extending from the tank to discharge upon the belt, said spout having a plurality of discharge openings depositing a like series of ribands of liquid upon the belt.

Signed at Seattle, King county, Washington, this 28th day of May, 1920.

JOHN F. PFEIFFER.
